METHOD OF INHIBITING BACTERIA IN
BRINE SYSTEMS

Daniel S. Dustin, White Bear Lake, and Jack W. Sigan,
Minneapolis, Minn., assignors to Archer-Daniels-Mid-
land Company, Minneapolis, Minn., a corporation of
Delaware

No Drawing. Filed Mar. 15, 1965, Ser. No. 440,020
5 Claims. (Cl. 210—64)

This invention relates to the use of water soluble furfuryl aliphatic dialkyl quaternaries as inhibiting and killing bactericidal agents, or bacteriostats. More specifically this invention relates to the use of furfuryl aliphatic dimethyl quaternaries (where the aliphatic group is derived from fatty acids) in secondary oil recovery, as bactericides, to control sulfate-reducing bacteria and other micro-organisms.

This application is a continuation-in-part of our pending application Serial No. 108,767, filed May 9, 1961, now abandoned.

The literature provides no discovered information on furfuryl quaternaries as bactericides. The furfuryl dimethyl alkyl quaternary bromides have been prepared where the alkyl group is C_1 through C_{18} . These preparations were tested as stimulators for the parasympathetic nervous system (Weilmuenster and Jordan, J.A.C.S., 67, 415, 1945 and Nabenauer, U.S. Patent 2,185,220) where the alkyl group is C_1 — C_5 and the bromides are used as stimulators of neuromuscular mechanisms in the body. In general, there has been a relatively strong consensus that C_{12} to C_{14} alkyl chain quaternaries containing a benzyl group are most effective for inhibiting and killing bacteria growths and that longer alkyl chains are less effective and not particularly desirable.

Accordingly, it is an object of this invention to provide highly effective bacteria inhibiting and killing furfuryl based quaternary compounds having long chain aliphatic groups derived from fatty acids.

Another object of this invention is to provide the art with a method of using furfuryl aliphatic dialkyl ammonium quaternaries as inhibiting and killing bactericides when prepared from primary aliphatic amines having aliphatic hydrocarbon groups of 8 to 22 carbon atoms and preferably long chain aliphatic groups of about 16 to 18 carbon atoms derived from fatty acids and the character obtained from tall oil acids, rosin acids, coco acids, palmityl, oleic, lauryl, stearyl, or similar long chain aliphatic groups of this character.

A further and particular object of this invention is to provide a method of controlling sulfate-reducing bacteria with our preferred furfuryl aliphatic dimethyl quaternary in the recovery of secondary oil in the oil refining art and more particularly furfuryl hydrogenated-tallow dimethyl ammonium chloride.

To the accomplishment of the foregoing and related ends, this invention then comprises the features herein-after set forth and more fully described and particularly pointed out by certain illustrative embodiments which are indicative of the ways in which the accomplishment of the herein described purposes are obtained.

In general the reactions involved in the preparation of the quaternaries, as herein described, are shown as follows:

2

wherein R is a saturated or unsaturated aliphatic group of 8 to 22 carbon atoms and preferably an aliphatic group of 16 to 18 carbon atoms derived from fatty acids. It will be recognized that other alkyl halides than the methyl chloride can be substituted. This would include materials such as ethyl chloride, methyl bromide, and the like. For example the furfuryl compounds contemplated herein have the following structure:

where

R is a C_8 to C_{22} aliphatic hydrocarbon group

35 R' is furfuryl

R'' is a short chain alkyl

X is a halogen atom

40 Reaction I can be carried out in 10—15% benzene solution and the water of reaction is removed by azeotroping with the benzene. The theoretical amount of water is obtained. A preferred method is the vacuum removal of water.

45 Reaction II is carried out in a pressure vessel capable of withstanding 400 p.s.i. pressure. The catalyst used is Raney Ni or Pd on charcoal, or a mixture of the two, or preferably copper chromite. The Raney Ni is used at 0.5% and the Pd at the 0.005% or 0.01% level as Pd and the copper chromite at 1—3%. The hydrogenation is carried out at 290—400° F. and 400 p.s.i. H_2 pressure. The reaction usually takes 2—3 hours. After filtration to remove the catalyst, the product is ready for quaternization (Reaction III).

50 Reaction III is carried out in a pressure vessel capable of withstanding about 100 p.s.i. pressure. The secondary amine is dissolved in isopropanol and charged to the vessel. The vessel is purged with CH_3Cl and the temperature raised to 180—200° F.; the pressure is then raised to 80—100 p.s.i. with CH_3Cl . Samples are withdrawn from the bomb and analyzed for free amine hydrohalide by titration.

55 When the amine hydrohalide concentration starts to build up, 50 or 60% aqueous NaOH solution is forced into the vessel in order to neutralize the HCl formed. The reaction is considered finished when the amine hydrohalide and free amine total less than 1.5%.

60 The reaction is preferably run so that the concentration of the final product is 50% to 75% solids in the isopropanol.

70

To illustrate this invention, a preferred furfuryl hydrogenated-tallow dimethyl quaternary was prepared as follows:

Example I

To 2532 gms. of hydrogenated-tallow based primary amines, molecular weight 262, were added 838 gms. of furfural over a 70 minute period. The temperature was held at 41-50° C. and a vacuum of 28-28.5 inches mercury was maintained to remove water of reaction. When no more water appeared to be coming off, the reaction was considered complete. Total reaction time was 1½ hours.

The Schiff base so prepared was hydrogenated in a Parr autoclave using 2% copper chromite as the catalyst. At 260-400° F. and a hydrogen pressure of 400 p.s.i.g. the hydrogenation was considered complete after 6 hours. The total amine nitrogen content was 4.3% and the secondary content 2.90%. Theoretical total amine nitrogen and theoretical secondary amine nitrogen content was calculated to be 4.1%.

The secondary amine was vacuum distilled to give a 94.8% distillation yield of a pale yellow liquid amine. The combining weight based on total amine nitrogen analysis was 340.

The distilled amine was quaternized with methyl chloride to give a furfuryl hydrogenated-tallow dimethyl ammonium chloride. To 340 gms. of amine, 108 gms. of isopropanol, 27 gms. of water, and 105 gms. of NaHCO₃ in a Parr autoclave was added methyl chloride gas at a rate sufficient to maintain a pressure of 50 p.s.i.g. After 5 hours of reaction at a temperature of 190° F. the material showed 0.57% free amine and 0.17% amine hydrohalide and the reaction was considered substantially complete. After cooling and venting the product was discharged and filtered.

Illustrative of another different furfuryl aliphatic di-

amine nitrogen. Using secondary amine prepared by the preceding method the corresponding quaternary was prepared. 2175 gms. of amine, 700 gms. of NaHCO₃, and 900 gms. of isopropanol were charged to an autoclave.

5 The temperature was brought to and held at 205-215° F. while methyl chloride was intermittently introduced to maintain a pressure of 60-112 p.s.i.g. Intermittent venting of CO₂ was necessary after which the methyl chloride was again fed into desired reaction pressures. After 7 hours of reaction the batch was cooled, the autoclave vented, and the reaction product filtered.

10 The furfuryl coco dimethyl quaternary product contained 76.5% quaternary salt, 1.6% free amine, 0.16% amine hydrohalide, 0.02% ash, and 5.06% water.

15 Illustrative of a method of application and use is as follows:

Example III

Secondary oil recovery by water flooding is adversely affected by micro-organisms which either directly or indirectly accelerate and induces sliming and corrosion. This sliming reduces filter efficiencies and reduces water injection rates through plugging of the recovery formation. Sulfate-reducing bacteria are of prime concern in these fields.

20 A series of tests were run to evaluate the furfuryl aliphatic dimethyl ammonium chlorides as bacteriostats against sulfate-reducing bacteria. Brines from five widely separated areas were used in these tests. The strains of Desulfovibrio utilized in these studies were grown from untreated infected source waters and the cultures were then isolated and purified. These fairly pure cultures were then reintroduced in various amounts (p.p.m.) into culture media made up from the collected field waters, the media were then incubated under controlled conditions, and the time of growth in days, if any, was noted. Results are shown in Table I.

TABLE I

Run	Quaternary used	Aq. medium treated	Specific gravity of aq. medium	Days noted for growth of Desulfovibrio						
				10 p.p.m.	15 p.p.m.	20 p.p.m.	25 p.p.m.	30 p.p.m.	40 p.p.m.	50 p.p.m.

**"None/21" means no growth of Desulfovibrio was noted after 21 days.

methyl quaternary, viz., furfuryl coco dimethyl quaternary, is the following:

Example II

1550 gms. of coco based primary amine, 690 gms. of furfuryl, and 150 gms. of benzine were charged to a 3-neck glass flask equipped with an agitator, thermometer, and water azeotrope separator. The reaction was carried out at 100-120° C. with azeotropic removal of the water of reaction. 143 cc. of water were collected. The Schiff base so prepared was vacuum distilled at 0.2-0.3 mm. Hg to a residue temperature of 190° C. A distillation yield of 88% was obtained.

The distilled Schiff base was then hydrogenated in a Parr autoclave using 0.005% palladium catalyst. At 215-304° F. and 400 p.s.i.g. hydrogen pressure the hydrogenation was substantially complete after 1½ hours. The product analysis showed 5.03% total amine nitrogen, 4.66% secondary amine nitrogen, and 0.37% primary

60 From the above it will be recognized that dependent upon the bacteria content the concentration (p.p.m.) of the quaternary will vary as the particular user finds necessary for his conditions. In many of the present tests an average of about 10-200 p.p.m. has been found to be satisfactory to reduce sliming and prevent filter clogging. However, more or less may be required and used according to water conditions, as known to those skilled in the art. In contrast to expectations the long chain hydrogenated-tallow furfuryl dimethyl ammonium chloride was surprisingly most effective in inhibiting or killing sulfate-reducing bacterial in oil well brines. In field application furfuryl hydrogenated-tallow dimethyl ammonium chloride quaternary was comparable to conventional and standard formulations of C₁₂-C₁₆ chain alkyl compounds presently used in oil recovery.

70 75 In performance tests of phenol coefficients (using the method described on page 87 of "Official Methods of

Analysis of the A.O.A.C., 8th ed., 1955), the hydrogenated-tallow furfuryl quaternary was superior to the coco counterpart and lauryl benzyl dimethyl quaternary. The following is illustrative of test data of long chain aliphatic furfuryl quaternaries (where the aliphatic group is derived from fatty acids) in comparison to several other recognized and commonly used materials.

TABLE II

Run	Material	Phenol coefficient at 20° C.	
		<i>Staphylococcus aureus</i>	<i>Escherichia coli</i>
1	Furfuryl cottonseed dimethyl quaternary.	1,000	260
2	Furfuryl palmityl dimethyl quaternary.	1,000	320
3	Furfuryl coco dimethyl quaternary.	260	80
4	Furfuryl tallow dimethyl quaternary.	660	170
5	Dicooc dimethyl quaternary	52	29
6	Soya trimethyl ammonium methosulfate.	900	140
7	Soya trimethyl ammonium chloride.	870	80
8	Dodecylbenzyl trimethyl ammonium chloride.	400	120
9	Furfuryl coco amine acetate.	24	60

Additional tests showing the furfuryl long chain aliphatic ammonium chloride quaternaries (where the aliphatic group is derived from fatty acids) are active against *Escherichia coli* and *Staphylococcus aureus* are shown in Table III. The test method used was that described in J.A.O.A.C., 41, No. 1, pages 34-36, 1958, using 200 p.p.m. of the quaternary, test water with a hardness of 500 p.p.m. and numbers controls of 93-125 million

A further series of innumerable personal tests involved mixing about one bottle cap full (about 1-2 oz.) of the furfuryl quaternary of Example I to a glass of water and used as hair rinses. The results of softness and conditioning for setting the hair proved amazing. Dandruff appeared to be completely removed, not to reoccur on weekly washing and like repeated rinsing of the hair.

In testing relatively concentrated solutions of these quaternaries, for toxicity, it is found that the hydrogenated tallow, coco and cottonseed furfuryl dimethyl ammonium chlorides were all quite similar toxicologically. The tests for acute oral toxicity (albino male rats), primary skin and dermal irritation (rabbits) and eye irritation (rabbits) showed the following values: acute oral LD-50 values are approximately 0.5 cc./kg. for the coco furfuryl quaternary and 0.7 cc./kg. for the hydrogenated tallow and cottonseed furfuryl quaternaries. It would appear that the furfuryl long chain aliphatic quaternaries, where the aliphatic group is derived from fatty acids, may all be considered to be in the class of materials slightly toxic by accidental oral ingestion, moderate skin irritants and severe eye irritants, in a manner typical of cationic surfactants.

Thus, while essentially finding application of the furfuryl long chain aliphatic quaternaries as useful in oil well brines, it will be recognized that other advantages in use as bactericidal control material in compounding hair formulations in supervised formulations for inhibiting or killing athletic foot and fungus growths, antiseptic cleaning solutions, and other analogous formulations are possible.

Modifications and alterations of this invention will be apparent to those skilled in the art without departing from

TABLE III

Run	Quaternary used	Exposure time, sec.	(Gram negative) <i>Escherichia coli</i>		(Gram positive) <i>Staphylococcus aureus</i>	
			Survivor count	Percent kill	Survivor count	Percent kill

We claim:

1. A method for treating brine containing bacteria, which comprises adding to said brine a compound of the formula:

where R is an aliphatic hydrocarbon having 8-22 carbon atoms derived from fatty acids, R' is furfuryl, R'' is selected from the group consisting of methyl and ethyl, and X is a halogen, the amount of said compound added to said brine being sufficient to inhibit the growth of said bacteria in said brine.

2. The method according to claim 1 wherein said compound is furfuryl tallow dimethyl ammonium chloride.

3. The method according to claim 1 wherein said compound is furfuryl hydrogenated-tallow dimethyl ammonium chloride.

4. A method for reducing sliming and preventing filter clogging in aqueous brine systems for secondary oil recovery, which comprises treating such brine with 10-200

parts per million of a compound having the general formula:

where R is an aliphatic hydrocarbon having 8-22 carbon atoms derived from fatty acids, R' is furfuryl, R'' is selected from the group consisting of methyl and ethyl, and X is a halogen.

5. The method according to claim 4 wherein said compound is furfuryl hydrogenated-tallow dimethyl ammonium chloride.
